Thomas J. Byrne
for Robt. Atchley, attorney.

UNITED STATES PATENT OFFICE.

THOMAS J. BYRNE, OF ERIE, PENNSYLVANIA, ASSIGNOR OF ONE-HALF HIS
RIGHT TO CLARK M. COLE, OF SAME PLACE.

IMPROVEMENT IN DEVICES FOR DRAWING BEER.

Specification forming part of Letters Patent No. 172,085, dated January 11, 1876; application filed
November 2, 1875.

To all whom it may concern:

Be it known that I, THOMAS J. BYRNE, of Erie, in the county of Erie and State of Pennsylvania, have invented certain new and useful Improvements in Devices for Drawing Beer; and I do hereby declare that the following is a full, clear, and exact description thereof, which will enable others skilled in the art to which it pertains to make and use the same, reference being had to the accompanying drawing, and to the letters of reference marked thereon, which form a part of this specification.

My invention relates to improvements in that class of devices employed for forcing air into barrels, kegs, and other similar vessels, in order to produce sufficient pressure within the same to cause liquid contained therein to flow readily therefrom when the spigot or tap is open, the nature of which will be hereinafter fully explained by reference to the drawings, in which—

Figure 1 represents a horizontal section of an ice-box, with a barrel or keg contained therein, with my invention applied thereto. Fig. 2 represents a sectional view of the air-pump. Fig. 3 shows a vertical section of the plug, and parts connected therewith. Fig. 4 shows a detached view of parts.

In each of the views similar letters of reference are employed to indicate corresponding parts wherever they occur.

L represents an ice-box, within which is supported a keg or barrel, A, provided with a spigot or tap, B, passing through to the exterior of the ice-box. G is an air-pump, provided with a cylinder, C, and cap g, through which passes the rod H, on the end of which is mounted the plunger I, to the forward face of which is, by means of a peg or screw, k', connected a valve, K, provided with openings k, and having a dished rim, K', extending forward from the same. Within the rim K' of the valve K is arranged a coiled spring, m, adapted at all times to keep the rim K' firmly fitting against the inner periphery of the cylinder G. The extreme end of the cylinder G is fitted with a pipe or tube, n, to which is attached a flexible tube, F, the opposite

end of which is affixed to a short pipe or tube, n¹, on which is mounted a clamp, E, in such manner that the end of the tube n¹ shall be about level with the forward face of the notched projection E' of the clamp E, and be capable of receiving an elastic washer or packing, n², as shown by Figs. 3 and 4. D represents a valve, provided with a hollow stem, d, having a screw-thread, d¹, formed on its periphery, adapted to be received and held in an opening formed in a plug, C, adapted to be inserted in the upper side of the barrel or keg A, or into an opening in an enlargement, C', in the spigot B, as shown by Fig. 1. The front end of the valve D is provided with a flat plate, D¹, having parallel sides D², and rounded ends D³, the diameter of which from D² to D³ being such as just to pass between the ends of the projections E', and its length such that when the clamp E is placed over it and turned around, as shown by Fig. 3, the rounded ends D³ shall be received and held securely within the recesses E² of the clamp E, thereby holding the end of the pipe n¹ (on which is arranged the washer or packing n²) within the conical end d² in such manner that the washer n² shall form a tight joint between the valve D and the pipe n¹. The end d³ of the hollow tube d is turned down and provided with an external cylindrical valve, p, adapted to cover a series of openings, p', in such manner as to prevent the egress of air from the barrel through the hollow tube d, but to allow of its readily being forced through the openings p into the barrel or keg from the air-pump G.

The operation of the apparatus is so well known, and, in view of the state of the art at the present time, it is unnecessary to describe the operation of the same.

Having thus described my invention, what I claim, and desire to secure by Letters Patent, is—

1. The combination, with the valve D, having a hollow screwed stem, d, plate D¹, conical opening d², passages p', and external cylindrical valve p, of the clamp E, tube n¹, and washer n², substantially as shown and described.

2. The combination, with the air-pump G,

pipe F, and plug, of the valve D, having a hollow screwed stem d, plate D¹, conical opening d², passages p', and external cylindrical valve p, and the clamp E, tube n¹, and washer n², substantially as and for the purpose described.

In testimony that I claim the foregoing as

my own I affix my signature in presence of two witnesses.

THOMAS J. BYRNE.
